MECHANICALLY OPERATED KNITTING
MACHINE

George F. Gast, Jersey City, N. J.

Application July 21, 1933, Serial No. 681,419

16 Claims. (Cl. 66—3)

This invention relates to a method of and means for knitting, and more particularly to a device in which the stitches are formed over a series of pins adjacent to an opening through which the knit fabric is passed as it is completed.

The usual practice to produce cylindrical fabrics, such as cord commonly known as "horse rein", is to use a body plate of suitable form such as a spool provided with mesh holding arms 10 mutually related and formed, to allow the insertion and manipulation of a hand knitting needle.

An object of the invention is to provide a simple and efficient device for mechanically producing a knit fabric heretofore produced by hand.

The above object is accomplished in accordance with the features of the invention by means of a knitting machine having a rotatable forming plate with a plurality of mesh holding arms or hooks mounted therein, and means to drive and hold said plate in predetermined positions. A hook or needle is driven in a given path, the locus of which resembles a figure 8 with a flat bottom and the parts are so arranged and related that 20 after the needle has thrown a new purl over a pair of the hooks on the forming plate, a partial rotation of the forming plate brings the next pair of hooks in front of the needle and a purl is thrown over these hooks. The operation is continued, forming a rounded fabric without interrupting or slackening the production of finished fabric in the machine.

The invention may be better understood by referring to the following detailed description 35 and the accompanying drawings, forming a part thereof, in which

Fig. 1 is a perspective view of a preferred embodiment of the invention;

Fig. 2 is a side elevation of the device shown in 40 Fig. 1;

Fig. 3 is a plan view of the device;

Fig. 4 is an end elevational view;

Fig. 5 is a sectional view of the forming plate, showing the path of the knitting arm or hook;

Fig. 6 is an enlarged plan view of the forming plate showing how it is threaded, and

Fig. 7 is a perspective view of another type of forming plate for producing a flat fabric.

Referring to the drawings which illustrate a preferred embodiment of the invention a housing 24, a thread container 41 and a tensioning standard 35 are mounted on a base 20 (Fig. 1). A rotatable forming plate 11 is mounted in a bearing 19 in the base 20 (Fig. 2). The forming plate 11 which is spool shaped has a base portion

12 on which a collar or ratchet 17 is mounted. The collar or ratchet 17 has notched out segments 18 as shown in Fig. 3. The forming plate assembly 11 is mounted in the wrist plate 48 and the bearing 19, then suitably secured on the 5 under side of base 20. In the upper portion of forming plate 11 are mounted mesh holding fingers or pins 15—15. In the embodiment shown are four pairs, the number of pairs of pins being optional. The number of notches in collar 17 10 must correspond with the number of pairs of pins. A slot 16 (Figs. 3 and 6) between each pair of pins 15—15 is cut wide enough to allow the hook member 42 to pass through. A circular opening 14 which has rounded shoulders at the 15 top where the purl is formed, extends entirely through the spool 11. A wrist plate 48 (Figs. 1, 3 and 5) is oscillatably secured to the base 20. A spring pressed holding latch 51 mounted on the base 20 is adapted to move into the notches 18 20 in the forming plate 11 to prevent backward rotation of the forming plate 11.

A pawl 49 is mounted on the wrist plate 48 and is spring pressed into the notches 18 of the collar 17. A link or pusher 47 which is pivotally attached by means of a pin 46 is also fastened to wrist plate 48 (Figs. 3 and 5). A shaft 30 projects through and is journaled in the housing 24. A hand crank lever 29 is secured to one end of shaft 30 and a crank disc 34 (Figs. 1 and 2) is secured to the other end of the shaft 30. Adjacent to the crank disc 34 is a cam 44. A gear 26 is secured to the drive shaft 30, within the housing 24. An intermediate idling gear 27 (Fig. 4) which is mounted on a shaft 61, meshes with gear 26. A gear 28 which is secured to a shaft 31 projecting through the housing 24, meshes with the intermediate gear 27. Gears 26 and 28 rotate at a ratio of 1 to 2, gear 28 making two revolutions to every one revolution of gear 26. Another crank disc 33 is secured to the shaft 31, outside the housing 24 and in the same plane with crank disc 34. Crank pins 36 and 37 are secured to crank discs 33 and 34 respectively (Fig. 2). When the crank pin 37 is at the top of its travel, the crank pin 36 45 is at the bottom of its travel. One end of each of links 39 and 38 is carried by and freely rotatable on crank pins 36 and 37 respectively. The link 38 is three-fourths the length of link 39. The distance between the center of shaft 30 and the 50 center of shaft 31 equals the length of link 39 plus the throw of the crank pin 37. The throw of crank pin 37 is the same as the throw of crank pin 36. The other ends of each of the links 39 and 38 are pivotally attached together at a point 55

40. A hook shaped portion or needle **42** is a part of the link **39** and projects beyond the pivot point **49**. The hooked shaped portion or needle **42** has a front slanted face **50** and a notched portion **52**.
 5 The link **47** is pivotally attached to link **57** by a pin **58** (Fig. 1). The link **57** is secured to one end of the bell crank lever **45**, and a spring **53** (Fig. 2) is secured to the other end of the bell crank lever **45**. The bell crank lever is pivotally mounted by means of a pin **59** to an upwardly projecting portion of the housing **24**.

10 The spring **53** which has one end secured to the bell crank lever **45**, has its other end secured by a pin **54** to the lower portion of the housing **24**.
 15 The tensioning standard **35** (Fig. 4) has a top portion **23** wherein are mounted pins **22**. The thread container **41** is a box, having a cover with a slot leading to an opening **43** through which the cord passes. A weight **25** which has two arms
 20 or horn portions **32** is clamped in any suitable manner to the finished "horse rein" **10**.

In another embodiment of the invention there is a body plate **55** (Fig. 7) which may be substituted for spool **11** to produce a flat fabric instead
 25 of the round "horse rein" type. The body plate **55** will have the same type pins **15-15** and slots **16**. A track **56** is used to guide the body plate **55** as it advances by means not shown. A shield **60** (Fig. 7) is mounted on base **20**, so that the fabric
 30 formed may be pulled over outer edge of base **20** by means of a clamp and weight not shown.

To operate the machine, it is mounted with spool **11** overhanging the supporting means. The spool **11** is threaded as shown in Fig. 6 by passing
 35 cord **13** through opening **14** in spool **11**, the cord then being wound around each pair of pins **15-15** in an anticlockwise direction. After passing around each pair of pins the feed cord **13** is then
 40 passed across the hooked face of pins **15-15**, above the already wound portion of the pin in front of hook **42** (Figs. 5 and 6). The feed cord **13** is then passed through the tensioning device **23** (Figs. 1, 2 and 3) and the ball or spool of cord **21** is deposited in the metal case **41**. The first
 45 few sets of purls are preferably formed by hand so that the fabric **10** may be pulled through the opening **14** sufficiently to allow the weight **25** to be clamped thereto.

When the hand crank lever **29** is turned in a
 50 clockwise direction it rotates the cam **44** in a similar direction at the same rate of speed. Each rotation of the cam **44** causes the movement of the bell crank lever **45**, against which it rides, to a position as shown in dotted lines in Fig. 2.
 55 The spring **53** returns the bell crank lever to its original position. The movement of the bell crank lever gives an oscillating motion to wrist plate **48**. The pawl **49** which is mounted on the wrist plate **48** imparts this motion in one direction to the spool **11** by means of the notched collar **17**, as shown in Figs. 2 and 3. The collar **17** is held after each partial rotation by the holding latch **51**. The amount of rotation of spool is predetermined, in this case a quarter of a revolution, since we have but four pairs of pins. The holding latch is so positioned that it will hold each pair of pins in turn directly in front of the path of travel of the hook member **42**. When the hand crank lever **29** is turned it also causes gears
 60 **26**, **27** and **28** to rotate. Crank discs **33** and **34** being connected to gears **26** and **28** rotate in the same relation. The rotation of these crank discs causes the links **38** and **39** to carry hook **42** in a given path, the configuration of which resembles
 65 a figure 8 with a flat bottom. The rotation of
 70

the hand crank lever **29** causes the hook **42** to be carried as shown in dotted lines in Fig. 5 between the pair of pins **15-15** through the slot **16**. The hook **42** allows thread **13** to slide over its slanted face **50** and is caught in the notched portion **52**.
 5 Thus the hook **42** sweeps between the pins **15**, catches the strand **13** and carries it out, clearing feed cord, and over pins **15**, forming a purl with the feed strand **13** which could not pass over pins, because of the hooked form of the pin.
 10 When the hook **42** has completed one cycle, the spool is rotated again through one-quarter revolution as described above. Thus the strand **10** is produced by a continuous rotation of the hand crank lever **29**.

15 It will be obvious that the embodiments herein disclosed are only illustrative and not exhaustive of the invention and may be varied in many ways without departing from the spirit and scope of the invention as pointed out in the appended claims.

20 What is claimed is:

1. In a knitting machine, a rotatable forming plate, a plurality of pairs of pins on said forming plate, a reciprocating hook, a cam and link arrangement for rotating said forming plate to bring each pair of pins in succession in front of said reciprocating hook and means for moving said hook between the individual pairs of pins.

2. In a knitting machine, a rotatable forming plate, a plurality of pairs of pins on said forming plate, a reciprocating hook, and means comprising a cam and link arrangement for rotating said forming plate to bring each pair of pins in succession in front of said reciprocating hook and means for moving said hook between the individual pairs of pins.

3. In a knitting machine, a forming plate, a plurality of pairs of pins on said forming plate, a hook, means for consecutively moving each pair of pins into operative relation with respect to said hook and a crank and link arrangement for moving said hook between the pair of pins in operative relation with respect to the hook.

4. In a knitting machine, a forming plate, a pair of pins on said forming plate, a hook adapted to move between said pins, and means to drive said hook comprising a crank for imparting horizontal motion to said hook and a crank and link arrangement for imparting vertical motion to said hook.

5. In a knitting device, a mechanically operated hook and a body plate having an annular series of pairs of pins for supporting the meshes of the fabric knitted, and having apertures between said pins to facilitate insertion of the mechanically operated hook which travels in a given path, the configuration of which resembles a figure 8 with a flat bottom.

6. In a knitting device, a body plate having an annular series of pairs of pins and apertures between said pins, a hook or needle which travels in a given path, forming a purl each time it passes between one of the pairs of pins, and cam and crank means to rotate the forming plate, so that each pair of pins is positioned consecutively before the hook or needle.

7. In a knitting device comprising a body plate for forming the fabric, and a hook or needle which travels in a given path to form purls with the cord as it is being fed to the forming plate, and cam and crank means to drive the forming plate in the desired direction before the needle.

8. The combination, in a knitting device of pairs of pins mounted in a body plate, which is

5 rotatably mounted in a bearing, and so synchronized as to rotate in an established relation with the movement of a hook which travels between the pairs of pins in a given path to form a purl, the configuration of the path of the hook resembling a figure 8 with a flat bottom.

9. A knitting machine comprising a supporting structure, a plate rotatably mounted thereon, a circular series of spaced fingers carried by said plate and adapted to retain windings of yarn around the series, an operating shaft rotatably mounted in said structure, a ratchet carried by said plate, a pusher mounted in said structure for actuating said ratchet, a cam carried by said shaft for actuating said pusher, a needle movably supported in said structure and adapted to loop the wound yarn over said fingers, and means connected to said shaft for operating said needle.

10. A knitting machine comprising a supporting structure, a plate rotatably mounted thereon, a circular series of spaced fingers carried by said plate and adapted to retain windings of yarn around the series, an operating shaft rotatably mounted in said structure, mechanism operated by said shaft for intermittently turning said plate, a needle carrier movably supported in said structure, a needle carried by said carrier and adapted to loop the wound yarn over said fingers, and crank means operated by said shaft for actuating said carrier.

11. A knitting machine comprising a supporting structure, a plate rotatably mounted thereon, a circular series of spaced fingers carried by said plate and adapted to retain windings of yarn around the series, an operating shaft rotatably mounted in said structure, a ratchet carried by said plate, a pusher mounted in said structure for actuating said ratchet, a cam carried by said shaft for actuating said pusher, a needle carrier movably supported in said structure, a needle carried by said carrier and adapted to loop the wound yarn over said fingers, and crank means operated by said shaft for actuating said carrier.

12. In a knitting device, comprising a body

plate for forming the fabric, a hook or needle which travels in a given path to form purls with the cord as it is being fed to the forming plate, and means for rotating the forming plate to a desired position, said last mentioned means including a wrist plate associated with the forming plate and a spring pressed pawl carried by the wrist plate.

13. In a knitting device comprising a body plate for forming the fabric, a hook or needle which travels in a given path to form purls with the cord as it is being fed to the forming plate, means for rotating the forming plate, and a spring pressed holding latch for holding the forming plate in the desired position.

14. In a knitting device comprising a body plate for forming the fabric, a hook or needle which travels in a given path to form purls with the cord as it is being fed to the forming plate, and a spring pressed holding latch for holding the forming plate in the desired position.

15. In a knitting machine, a rotatable forming plate, a plurality of pairs of pins on said forming plate, a moveable hook the configuration of the path of which resembles a figure 8, a crank and link arrangement for moving said hook between each pair of pins, a cam and link arrangement for consecutively moving each pair of pins in front of said hook, and a latch for holding the forming plate in the desired position.

16. In a knitting machine, a rotatable forming plate, a plurality of pairs of pins on said forming plate, a reciprocating hook, and means comprising a cam and link arrangement for rotating said forming plate to bring each pair of pins in succession in front of said reciprocating hook and means for moving said hook between the individual pairs of pins comprising two crank discs, and a link secured between one of said crank discs and said hook, the other of said crank discs making two revolutions for each revolution of the first mentioned crank disc.

GEORGE F. GAST.
